UNITED STATES PATENT OFFICE.

ROGER I. ROSS, OF TROY, OHIO.

GUM-TAPE CUTTER AND MOISTENER.

1,392,358.

Specification of Letters Patent. Patented Oct. 4, 1921.

Application filed June 10, 1919. Serial No. 303,151.

To all whom it may concern:

Be it known that I, ROGER I. Ross, a citizen of the United States, residing at Troy, in the county of Miami and State of Ohio, 5 have invented certain new and useful Improvements in Gum-Tape Cutters and Moisteners, of which the following is a specification.

This invention relates to a device for cutting and moistening gummed tape, and the object thereof is to feed a strip of gummed tape over a moistener and to cut off the moistened portion.

Another object is to provide a device 15 adapted to feed a strip of tape from a roll over a moistener and a cutter for cutting off the moistened strip from the roll, the feeding means being adapted to actuate the cutting means.

20 A further object is to provide a device adapted to feed gummed tape from a roll over a moistener and a cutter for cutting off the moistened strip, the cutter being adapted to be actuated when the feeding of the 25 tape is interrupted.

A further object is to provide a device 30 for feeding tape from a roll over a moistener and to cut off the moistened portion of the tape from the roll and means whereby the length of the moistened portion may be regulated at will.

With the above and the related objects in view this invention comprises the construction, combination and arrangement of parts 35 hereinafter described, a preferred embodiment whereof is illustrated in the accompanying drawings and is embraced within the scope of the appended claim.

In the said drawings:

40 Figure 1 is a side elevation of my cutter and moistener partly in section to disclose the operating means;

Fig. 2 is a central section of Fig. 1;

Fig. 3 is a reverse side elevation of my 45 device;

Fig. 4 is a front elevation thereof, and

Fig. 5 is a detail showing an adjusting device in connection therewith.

Referring more particularly to the drawings for a detail description of my invention, 50 6 represents a frame provided with bearings for a reel 7 and with a tank 8 opposite said bearings. Intermediate the bearings and tank the frame is provided 55 with a gear chest 9. The chest 9 is provided with a bearing for a shaft 10 which

carries an intermittent gear 11. The intermittent gear is in mesh with a pinion 13 mounted on a shaft 14 carrying a roller 15. A roller 16 is mounted on a shaft 17 parallel with the shaft 14. On the shaft 10 is also mounted a spur gear 12 in mesh with a pinion 19 mounted on a shaft 20 supported by bearings of the tank 8. On the shaft 20 between the sides of the tank is 60 mounted a pulley 21 driving a belt 22 running over idlers 23. On the frame 6 rearwardly of the tank 8 and in front of the roller 15 is fixedly mounted a knife edge 24. A knife edge 25 adapted to coöperate with the knife edge 24 is fulcrumed at one end on a bracket 26. A rod 27 is pivotally connected at its upper end with the free end of the cutting edge 25 and is projected through and slidingly supported by brackets 28 and 29. The rod 27 carries a coil spring 30 connected therewith at one end and with a bracket 28 at its opposite end, and is provided with a pin 31 intermediate the brackets 28 and 29. The shaft 10 is 65 adapted to be operated by a crank 32 provided with a handle 33. On the shaft 10 between the frame 6 and the crank 32 is mounted a sleeve 34 provided with an arm 35 and with ears 36. The ears 36 are provided with bearings for a pin 37 carrying a latch 38 adapted to register with a recess 70 75 80 85 90 95 100 105 110 of the crank 32.

The operation is as follows:—The free end of a gummed roll of tape 40 mounted on the reel 7 is passed between the rollers 15 and 16 between the knife edges 24 and 25 and over the belt 22. When it is desired to moisten and cut off the moistened strip of tape the latch 38 is inserted in the recess 39 and the crank 32 turned to rotate the shaft 10. The gear 11 meshing with the gear 13 rotates the roller 15, causing the tape to feed between said roller 15 and the roller 16 until the portion of the gear 11 free of gear 18 teeth begins to roll over the pinion 13 which interrupts the feeding of the tape. This coincides with the arm 35 in position to engage the pin 31. The further movement of the crank 32 causes the arm 35 to bear against the pin 31 which forces the rod 27 downwardly compressing the spring and causing the knife edge 25 to register with the knife edge 24 shearing off the strip fed through it from the rest of the roll. During the rotation of the shaft 10 the gear 18 in mesh with the pinion 19 mounted on the shaft 20 causes

the pulley 21 to rotate and drives the belt 22 through the water of the tank 8 which wets the surface and as the wet belt moves under the strip of tape it moistens it.

- 5 From the above it will be understood that during each revolution of the crank 32 a strip is paid out and moistened and cut off and that at the time when the cutting off takes place the feeding is stopped since the 10 cutter is operated during the interval when the smooth portion of the gear 11 is in mesh with the pinion 13. If a longer strip is to be cut off the latch 38 is forced out of the recess 39 and the sleeve 34 will be free to 15 move on the shaft 10 so that the turning of the shaft will not transmit any motion to the sleeve and the arm 35 will not be able to actuate the cutter. When it is desirable to cut off a certain length of tape the latch is forced in the recess 39 and the turning of the shaft 10 will cause the arm 35 to force 20 the rod 27 downwardly until the arm is forced off said pin when the spring 30 causes

the rod 27 to resume its normal position and move the knife edge 25 away from the knife edge 24.

Having thus described the invention, what is claimed as new is:

The combination of a frame, means for feeding a strip over the frame, means for moistening the strip, a cutter pivoted at one end at one side of the frame and extending across the frame between the feeding means and the moistening means, a rod slidably mounted on the opposite side of the casing 35 and connected at its upper end to the free end of said cutter, yieldable means for holding said rod normally raised, a pin projecting laterally from the said rod, a crank mounted upon the side of the frame, a tappet 40 arm carried by said crank and adapted to impinge against said pin, and means driven by said crank for operating the feeding and moistening means.

I testimony whereof I affix my signature. 45
ROGER I. ROSS. [L.S.]
